CABINET

John J. Lubberts and Lambert J. Mulder, Grand Rapids,
Mich., assignors to Tomlinson of High Point, High
Point, N. C., a corporation of North Carolina

Application March 15, 1957, Serial No. 45,275

Term of patent 14 years

(Cl. D33—19)

FIG. 1

Fig. 1 is a front perspective view of the cabinet embodying our new design;

Fig. 2 is a rear perspective view thereof; and

Fig. 3 is an enlarged detail of one of the panels shown in Fig. 1.

The characteristic feature of the cabinet design resides in the arrangement of the parquet units on the compartment doors and their relation to and their association with the shelf units in the end of the cabinet.

We claim:

The ornamental design for a cabinet, substantially as shown and described.
